(57) **CLAIM**

I claim the ornamental design for a hooded garment, as shown and described.

DESCRIPTION

FIG. 1 is a front perspective view of a hooded garment showing my new design;

FIG. 2 is a front elevation view thereof;

FIG. 3 is a right side view thereof, the left side being a mirror image;

FIG. 4 is a rear elevation view thereof; and,

FIG. 5 is a top plan view thereof.

A design bottom side view is not applicable and has been omitted.

A design left side perspective view has been omitted, as it is a mirror image of the right side perspective view of FIG. 3. The contrast in shading between the hood portion and the face-covering portion of the hooded garment represents an exemplary contrast in appearance only and does not represent any particular color, material, texture or finish. The broken lines around the opening of the hood represent a stitching and form no part of the claimed design. The broken lines showing the remainder of the hooded garment are for environmental purposes only and form no part of the claimed design.
